UNITED STATES PATENT OFFICE.

MATHIAS JENSEN, OF ASTORIA, OREGON, ASSIGNOR OF ONE-HALF TO THE JENSEN CAN FILLING MACHINE COMPANY, OF SAME PLACE.

SEAMING-MACHINE.

SPECIFICATION forming part of Letters Patent No. 443,415, dated December 23, 1890.

Application filed September 4, 1890. Serial No. 363,878. (No model.)

To all whom it may concern:

Be it known that I, MATHIAS JENSEN, of Astoria, in the county of Clatsop and State of Oregon, have invented a new and Improved 5 Machine for Capping and Crimping Cans, of which the following is a full, clear, and exact description.

The invention consists in an improved mode of applying the same principle as 10 adopted in my prior invention shown and described in United States Letters Patent No. 376,804, granted to me January 24, 1888.

The object of the invention is to increase 15 capacity and insure certainty, especially in capping and crimping cans after the same are filled without spilling the contents.

Reference is to be had to the accompanying 20 drawings, forming a part of this specification, in which similar letters of reference indicate corresponding parts in all the figures.

Figure 1 is a front view of the improvement. Fig. 2 is a rear view of the same. Fig. 3 is a plan view of the same. Fig. 4 is an end elevation of the same with the frame in section, as indicated on the line *x x* of Fig. 1. Fig. 5 is a longitudinal sectional view of the heading and feeding device on the line *y y* of Fig. 4. Fig. 6 is a sectional side elevation of the can-body, feeding-arm, and cap-releasing device, with adjacent parts. Fig. 7 is an enlarged sectional side elevation of the disk for holding the cap in place while crimping. Figs. 8 and 9 are face views of the cams. Fig. 10 is a plan view of the improvement with 25 the main frame and the driving mechanism removed. Fig. 11 is a similar view of the same in a different position with parts broken out. Fig. 12 is a like view of the same in another position and with parts removed, showing the can-body and the feed and delivery arm. Fig. 13 is a plan view of the can-body support of the heading device. Fig. 14 is a plan view of the crimping device; and Fig. 15 is a plan view of the heading device, showing 30 the mechanism for opening and closing the cone-guides.

The main driving-shaft *H*, from which the several parts are actuated to move in unison, is mounted to turn in suitable bearings in the 35 lower part of the main frame *A*, and carries at its inner end a bevel gear-wheel *H'*, in

mesh with a bevel gear-wheel *H²*, secured on a vertically-arranged shaft *H³*, mounted to turn in suitable bearings, of which the lower one is on the main frame *A* and the upper 55 one on the table *B*.

On the shaft *H³* is secured a gear-wheel *H⁴*, meshing into a gear-wheel *H⁵*, mounted to turn on a stud *H⁶*, secured on the main frame *A*, the hub of the gear-wheel *H⁵* carrying a 60 gear-wheel *H⁷*, in mesh with a large gear-wheel *H⁸*, secured on a shaft *C'*, extending vertically and supporting the disk *C*, for carrying the can-bodies. Thus when the main driving-shaft *H* is rotated the disk *C* is turned 65 in the direction of the arrow *a'*. (See Fig. 3.) The gear-wheel *H⁵* also meshes into a gear-wheel *H⁹*, secured on the lower part of a vertically-arranged shaft *D'* of the heading device *D*. 70

On the upper end of the shaft *D'* is secured a pulley *E'*, over which passes a cross-belt *E³*, also over a pulley *E²* on the upper end of the shaft *E'*, which latter carries the cap-carrying disk *E* in the direction of the arrow *c'*. (See 75 Fig. 3.)

On the lower end of the shaft *H³* is secured a pulley *I*, over which passes a crossed belt *I'*, also passing over a pulley *I²*, secured on the lower end of a shaft *I³*, arranged vertically 80 and mounted to turn in suitable bearings on one side of the main frame *A*. On the upper end of this shaft *I³* is secured a pulley *I⁴*, over which passes a belt *I⁵*, also passing over a pulley *I⁶*, secured on the upper end of the shaft 85 *G'* of the crimping device *G*. (See Figs. 1 and 3.)

A rail *B²* is secured on the table *B* and extending partly around and over the outer edge of the disk *C*, and a disk *J* is secured by its 90 arm *J'* on the table *B* and held concentric over the disk *C*, so that it and the rail *B²* serve to guide the can-bodies while carried on the disk *C*. (See Figs. 1, 10, and 11.)

On the disk *J* are posts *J²*, which support a 95 ring *J³*, and levers *J⁴*, *J⁵*, and *J⁶* are held on pivots *J⁷* in and between said disks *J* and the ring *J³*, with their outer ends projecting in the path of the can-bodies and their inner ends against pins *J⁸*, secured on a disk *J⁹*, mounted 100 to turn on a shaft *C'*, and pivotally connected by a link *J¹⁰* with an arm *K*, which is mounted

on three cranks K', K², and K³. The latter two are pivoted in the table B, and the crank K' is secured in the upper end of the shaft H³, as seen in Figs. 1, 10, and 11.

5 The pivot J has springs J¹¹ coiled thereon, with one end fixed in the pivot and the other in the ring J³, so as to hold the levers J⁴, J⁵, and J⁶ in position, as shown in Fig. 10.

The arm K by its swinging motion, and said 10 connection just described moves the levers J⁴, J⁵, and J⁶ intermittently in position, as shown in Fig. 11.

The object of the levers J⁴, J⁵, and J⁶ is to 15 stop the can-bodies on the disk C and allow them to pass only at proper times to meet the fork K⁵ on the arm K, by which they are moved off the disk C against the lever L⁷, which is pivoted in a guide-plate B³. (See Figs. 10, 11, and 12.)

20 The lever L⁷ is connected by intermediate links with a stop-pin L' in the passage of the caps, which comprises a cap-releasing device, the same as in my previous invention referred to, with the exception of the intermediate 25 links, which might be made in different ways; but the connection is preferably made as follows:

The stop-pin L' is on the end of a rod L², pivoted to an arm L³, fixed on a pivot L⁴ above 30 the table F. The pivot L⁴ is journaled in the tables F and B, and between the tables is an arm L⁵, also secured on the pivot L⁴, and with its free end engaging a pin L⁶ in the lever L⁷. (See Figs. 4, 10, and 11.) A coil-spring L⁸ on the pivot L⁴ under the table B serves to hold the releasing device in position, as shown in Figs. 10 and 11.

Above the disk E is a fixed cover E⁶, with a plate E⁵ and a flange E⁷ on its under side, 40 which serves to guide the caps while carried on the disk E. (See Figs. 5 and 10.) In the plate E⁵ is a slot E⁸, in which slides the stop-pin L', and opposite is another stop-pin N, fixed on the end of a lever N', secured on a 45 pivot N², journaled in the cover E⁶, and on the other end of the lever N' is a pin N³ to engage a cam N⁴ on the swinging arm K, which actuates the stop-pin N at intervals, so that only one cap is allowed to pass while the stop-pin L' is absent from the cap. A spring N⁶ 50 on the pivot N² serves to hold the levers with the stop-pin N in position, as shown in Fig. 1.

When a can-head is released from the stop-pins L' and N, it is carried forward on the 55 disk E against the curved guide-plate E⁹, and at the same time a can-body is moved into the heading device D on the plungers O and O' by the inner prong of the fork K⁵ on the swinging arm K. (See Figs. 5 and 12.)

60 The heading device D is mounted on the upright axle D' as follows: A circular table D² is secured on the axle D' flush with the table B. This table D² carries the said plungers O and O' opposite each other. (See Fig. 5.)

65 Above the table D², secured on the shaft D', is a plate D³, with semicircular openings D⁴ opposite each other to hold the can-bodies

on the plungers O and O', and above the plate D³ on the shaft D' is a circular table D⁵, with two tapered holes D⁶, fixed opposite each other and in line with the plungers O and O'. The table D⁵ has a circular recess on top, in which are fitted two semicircular plates P' and P², each having one-half of a conical guiding-hole P³ and P⁴ on each end and made in conformity with the fixed tapered holes D⁶, so that when either ends of the plates P' and P² meet over the fixed hole D⁶ the two half-guides P³ and P⁴, with the fixed hole D⁶, will then form an entire conical guide or tapered 80 hole P, as shown in Figs. 5 and 15.

Above the table D⁵, secured on the shaft D', is a plate D⁸, in the under side of which are fixed two can-head passages D⁹, opposite each other, and so fixed that when a can-head is held against the semicircular end of either one of said passages D⁹ it is then directly over the small end of the tapered hole P, as seen in Fig. 5.

The plates P' and P² are adapted to open and close either side alternately, so that when one side closes the other side opens by the same action, and to insure the plates to close and form accurately in conjunction with the fixed tapered holes D⁶ pins P⁷ are secured in the table D⁵, projecting in slots P⁸ in the plates P' and P², as seen in Fig. 15.

The plates P' and P² are actuated by the following means: On each of the plates P' and P² are two adjustable plates P⁵ and P⁶, and between the latter are oscillating eccentrics Q and Q', fixed on short axles Q² and Q³, on the upper ends of which are also fixed two triangles Q⁴ and Q⁵, engaging two stationary cams Q⁶ and Q⁷, secured to the main frame A. (See Figs. 1, 5, and 15.) The axles Q² and Q³ are journaled in two arms D⁷, fixed on the plate D⁸, secured on the heading device D, so that by the revolution of the heading device D the said triangles Q⁴ and Q⁵ will alternately engage one the inner cam Q⁶ and the other the outer cam Q⁷ at the same time, and thereby turn the eccentrics Q and Q' in opposite directions, so as to close one side or the other of the plates P' and P² by acting on the plates Q⁵ and Q⁶, and when closed it is also securely locked by the position of the eccentrics Q and Q', as shown in Fig. 15. When so closed and locked, the conical guiding-hole P is then in order to receive and support a cap on the small end, and the entire hole P serves to guide the end of a can-body into the cap. (See Fig. 5.)

The guiding parts of the plates P' and P² should be made of steel and hardened, as the irregularity in diameter of ordinary can-bodies is such that it is necessary to taper the ends of the large cans before entering the cap, and which subjects the plates P' and P² to considerable friction.

The plungers O and O' in the table D², previously mentioned, have shanks O², with their lower ends engaging the free ends of levers O⁴ and O⁵, respectively fulcrumed on the

lower side of the table D². Each lever O⁴ and O⁵ carries a friction-roller O⁶ to travel on a cam O⁷, secured on the main frame A, as plainly seen in Fig. 5.

5 The can-bodies are pushed one at a time over the table B into the heading device D on the plunger O or O' by the fork K⁵ on the arm K, and on the turning of the heading device D the plungers O or O' are pressed upward by the free ends of the lever O⁴ and O⁵ as its friction-roller O⁶ travels up the incline of the cam O⁷, so that a can-body on either one of the plungers O or O' is forced upward, with its upper end guided and tapered, if necessary, by the walls of the conical guiding-hole as it is forced through it. While a can-body is thus forced up and before its upper end is through the small end of the conical guiding-hole P a cap is placed over said hole P, so that the can-body is rounded, sized, or tapered and forced into the cap by the one upward stroke of the plunger O or O'. The cap is moved and held over the guiding-hole P by the following means: Two flanges 25 R and R' on arms R² and R³ are fastened on the plate D⁸ and extend to pass alternately over part of the disk E. (See Fig. 10.) When a can-cap is released, as stated before, it is carried on the disk E toward the heading device D and into the path of the flanges R and R', so that either flange overtaking said caps will push it forward, while the inner edge of the plate E⁹ guides it into one of the can-head passages D⁹. The flange R or R' leaves the cap and passes through a semicircular recess E¹⁰ in the guide-plate E⁹. The passage D⁹, in which the cap is now entered, carries it forward on the revolution of the heading device D, while the fixed plate E⁹ guides the cap in against the end of the passage D⁹. In order to hold the cap accurately without positive fit, a spring-pressed plate S is provided, fitted to slide transversely in the plate E⁹. On the plate S is fixed a pin S', passing through 45 a slot in the plate E⁹ and being pressed on by the free end of the spring S², secured on the top of the plate E⁹. (See Fig. 10.) The cam O⁷ and the guide-plate E⁹ are fixed in such relation to each other that the plate E⁹ will push the cap 50 against the end of the passage D⁹ just before the end of the can-body is forced through the small end of the guiding-hole P by the upward incline of the cam O⁷. At the same time as the upper end of a can-body is thus 55 pushed through the hole P into the cap a succeeding can-body is entering into the heading device D at the opposite side, as shown in Fig. 5. As soon as the can-head has passed the spring-pressed plate S, the 60 plates P' and P² are actuated to reverse, as previously described, so as to close and form a conical guiding-hole P on the opposite side for the succeeding can-body to be capped like the first, and this also separates the plates P' and P² from the can-body just capped. The 65 capped can is then over the downward incline of the cam O⁷, and as the heading device

D continues to revolve the capped can follows the plunger O or O' downward by its own gravitation, while the succeeding can-body is forced up into the cap on the opposite side of the heading device D. When the capped can is lowered sufficiently, the rear wall of the semicircular opening D⁴ crowds it out of the heading device D against the arms T at T'. (See Fig. 12.) The capped can is now taken by the fork K⁶ on the arm K and pushed forward over the disk U in the crimping device G between the guide-rail B⁴ and the arm T. (See Fig. 12.)

8c The crimping device is constructed as follows: A shaft G', with the disk G² on its lower end and a pulley I⁶ on its upper end, is fixed in bearings and driven to revolve from the shaft H³, as previously described. In the under side of the disk G² is a recess for the admission of about one-half the cap. To hold the can while revolving in the recess are spring-pressed plates to discharge the cap from the recess after it is crimped to the body. (See Figs. 1, 6, and 7.) Directly under the disk G², in a recess B⁵ in the table B, is seated a revolvable disk U, with a shank U', extending downward and engaging with a steel plate U², cushioned by a spring U⁶ in the free end of a lever U³, which latter is fulcrumed on the under side of the table B and carries a roller U⁴ in contact with a cam U⁵, secured on the shaft H³. (See Fig. 6.) A crimping-disk V in an arm V', having a slot V², in which projects the head of a bolt V³, projecting from an arm V⁴, is secured on a vertical shaft V⁵, mounted to turn in suitable bearings on the table B. The said bolt-head V³ is eccentric and serves to adjust the crimping-disk V tight or loose against the flange of the cap, according to its position. On the lower end of the shaft V⁵ is secured an arm V⁶, carrying a friction-roller V⁷, held in contact with a cam V⁸, secured on the shaft H³ above the cam U⁵, previously mentioned, as shown in Figs. 1 and 14. A spring V⁹ pulls on the arm V⁶, so as to hold its roller V⁷ in contact with the cam V⁸. The cam U⁵ is so arranged that at the time a can is passed on the disk U the lever U³ swings upward, so as to press the can with its cap into the recessed bottom of the disk G², which latter then revolves the can and the disk U, and at the same time as the can commences to revolve the disk V is actuated by the cam V⁸ through the connection just described, so that its sharp edge is pressing the edge of the flange of the cap against the can-body. The spring V⁹ by its connection, as described, removes the disk V from the cap when the cam V⁸ permits it. (See Figs. 1, 3, 5, and 14.) When the can is crimped, the disk U is lowered with the crimped can on it, and the arm K is then on its forward stroke, so that the fork K⁷ takes the can and pushes it forward in the passage between the arm T and the guide-rail B⁴.

On the front of the table B, in line with the passage of the crimped cans, is a tipping-rail

W, extending to about the middle of the said guideway, so that the finished can when pushed forward is tipped over to one side, assisted by an inclined rail W' on the top of the table B. The tipped can rolls forward to the soldering-machine on a rail W² and the rail W⁴, which is a continuation of the guide-rail B⁴. A guard-rail W³ prevents the can from rolling off the other rails.

10 The operation is as follows: When the machine is set in motion, as previously described, the filled can-bodies are passed, one or more at a time, over the table B onto the revolving disk C between the arms J' of the fixed disk J and the guide-rail B². The caps of the cans are passed with their flanges downward over the table F onto the disks E to be carried along by the latter until they strike against the stop-pins L' and N. The can-bodies on 15 the disk C move forward until temporarily interrupted in their forward movement by the levers J⁴, J⁵, and J⁶, which serve to insure proper meeting of the can-bodies with the fork K⁵ of the arm K, which moves the can-body 20 from the disk C across the table B against the lever L', so that the releasing device L is actuated, and at about the same time the lever N' is operated on by the cam N⁴, so that the cap held by the stops L' and N is freed 25 and moves forward at the time the can-body moves onto the table D² over the respective plunger O or O'. The flange R or R' then overtakes the cap and pushes it forward while the plate E⁶ is guiding it into and against the 30 end of the passage D⁶ over the conical guiding-hole P, so that it is just in time to receive the upper end of the can-body, which is pushed upward through the guiding-hole P into the cap by the plunger O or O'. When the can- 35 body has fairly entered the cap, the plates P' and P² are actuated to close and lock the opposite side for a succeeding can to be capped in the same manner, and this also separates the plates P' and P² from the capped can, 40 which is then lowered on the plunger O or O', while a succeeding can-body is forced up into a cap in the opposite side of the heading device D the same as the first, and when the capped can is sufficiently lowered then it is 45 against the curved arm T', by which it is guided out of the heading device. The fork K⁶ of the arm K now takes hold of the capped can and moves it forward between the arms T and the guide-rail B⁴ over the disk U, which 50 then rises at the receding of the fork K⁶ and presses the cap of the can into the recessed disk G², so that the can and the disk U revolve with the said disk G², and then the crimping-disk V is moved against the flange 55 of the cap and presses the same inward, thus crimping the cap securely onto the upper end of the can-body. When this is accomplished, the crimping-disk V is disconnected from the 60 cap of the can, and the latter descends with the downwardly-sliding disk U until said disk is seated in its seat B⁵ in the table B. The fork K⁷ of the arm K now engages the can 65

and moves it forward in the guideway to about the center of the disk V, and at the next movement of the arm K the outer prong 70 of the fork K⁷ touches the rear side of the can and again moves it forward in the guideway. The next can following is moved against the first can, so that the latter slides up the incline W' and moves with its side against the 75 arm W, so that the can is tipped over and falls onto the rails W² and the continuation of the rail B⁴ to roll off to the soldering-machine.

It is understood that were the disks C and E continuously supplied with caps and cans, then the mechanisms for regulating the can-bodies and releasing the can-heads would not be necessary, as the fork K⁵ can only move one can at a time from the disk C, and the caps 80 would readily be stopped on the disk E by a simple spring that would yield sufficiently to allow a can-head to pass when one of the flanges R or R' strikes it. The spring would again retain its position to hold the next can- 85 head until the other flange R or R' strikes and moves it away like the first; but, considering its greater capacity, it cannot be fully supplied at all times by one man unless he be unusually expert and careful. Hence the regulating mechanism is supplied, so that the can-bodies placed at random on the disk C may be properly entered into the heading device without being crushed and the caps prevented 90 from entering therein when there is no can-body to receive them.

Having thus fully described my invention, what I claim as new, and desire to secure by Letters Patent, is—

1. In a machine for capping and crimping cans, a heading device provided with two semicircular plates, each plate having one-half conical guide at each end and adapted to close on either one of two sides alternately and thereby form an entire cone-guide or tapered hole on one side while opening and separating on the other side, substantially as shown and described.

2. In a machine for capping and crimping cans, the combination, with a recessed table having two fixed conical guiding-holes opposite each other, of two semicircular plates fitted in the said recess, adapted to close and form an entire conical guiding-hole on either one of two sides alternately and in conjunction with either one of said fixed conical guiding-holes, two passages adapted to receive and guide the can-caps one at a time over said entire cone-guide when closed on either side, and means to move and stop the can-heads one at a time in said passage, while the ends of the can-bodies one at a time are guided through said entire cone-guide into the can-head and a headed can released at the opposite side, substantially as shown and described.

3. In a machine for capping and crimping cans, the combination, with a table having two tapered guiding-holes fixed opposite each other, of two semicircular plates fitted into

5 said table and adapted to close at either one of two sides and form an entire tapered guiding-hole in conjunction with either one of said fixed holes, stop-pins on the said table through slots in the said plates to insure the said conjunction, and means to move and stop the can-heads one at a time over the small end of said entire guiding-hole when closed on either side and while the end of a can-body 10 is forced through said hole into the can-head, and a headed can removed at the opposite side alternately, substantially as shown and described.

4. In a machine for capping and crimping 15 cans, the combination, with a revoluble can-heading device provided with flanges to push the can-caps forward with the revolution of said heading device, of a fixed plate or device adapted to guide the can-caps one at a 20 time into said heading device and hold it while the end of a can-body is forced into it, with means to actuate the same, substantially as shown and described.

5. In a machine for capping and crimping 25 cans, the combination, with a revoluble disk horizontally arranged and provided with an even surface to carry the can-heads on, of a fixed guideway adapted to guide the can-heads while carried on said even surface, 30 a stop to stop the can-caps while said even surface slides under the same, and means to move the can-caps one at a time from said disk into a heading device, substantially as shown and described.

35 6. In a machine for capping and crimping cans, the combination, with a revoluble disk horizontally arranged and provided with a smooth and even surface to carry the can-bodies on, of a fixed guideway adapted to 40 guide the can-bodies while carried on the said smooth surface, a stop over said smooth surface to stop the can-bodies while said disk revolves, and means to move the can-bodies one at a time from said stop into a can-head- 45 ing device, substantially as shown and described.

7. In a machine for capping and crimping cans, the combination, with a revoluble disk

horizontally arranged and provided with a smooth and even surface to carry the can- 50 bodies on, of a fixed guideway to guide the can-bodies while carried on said smooth surface, a stop over said smooth surface to stop the can-bodies while said disk revolves, with means to move the can-bodies one at a 55 time from said stop into a heading device and again remove the headed cans from the same to a crimping device, substantially as shown and described.

8. In a machine for capping and crimping 60 cans, a crimping device mounted on a frame comprising a revoluble disk mounted in and flush with a table fixed in said frame, an arm pivoted in fixed bearings under said table, having a plate cushioned in the end thereof 65 and adapted to raise and lower the said disk, a second disk mounted and rotated in fixed bearings above the said table, adapted to receive and revolve the can when raised on the said first disk, a third revoluble disk journaled in an arm pivoted in a fixed support on the said table, and means to automatically place the cans one at a time between said first and second disks and revolve the same while the periphery of said third disk is applied 70 against the flange of the can-head, with means to release and discharge the crimped can, substantially as shown and described.

9. In a machine for capping and crimping 80 cans, the combination, with a horizontally-ar- ranged disk rotated in fixed bearings and flush with a table having a smooth surface adapted to carry the cans in an upright posi- 85 tion, of a stoppage across said smooth sur- face to stop the cans while said disk revolves under, a swinging arm or device adapted to move the can-bodies from said stoppage to and from a crimping device, so that one fol- 90 lows another in succession, and means to actuate the same, substantially as shown and de- scribed.

MATHIAS JENSEN.
